(57) **CLAIM**

I claim the ornamental design for a spring-loaded weather seal for garage door, as shown and described.

DESCRIPTION

FIG. 1 is a perspective view of an enlarged spring-loaded weather seal for garage door showing my new design; FIG. 2 is an enlarged end elevational view thereof, the elevational view of the opposing end being a mirror image thereof;

FIG. 3 is an enlarged top plan view thereof;

FIG. 4 is an enlarged front elevational view thereof;

FIG. 5 is an enlarged rear elevational view thereof;

FIG. 6 is an enlarged bottom plan view thereof; and,

FIG. 7 is a reduced perspective view showing the spring-loaded weather seal for garage door in use; the broken lines depict environmental structure for illustrative purposes only and form no part of the claimed design.
